(57) **CLAIM**

The ornamental design for a sterilizer for microphone, as shown and described.

DESCRIPTION

FIG. 1 is a front, top, right side perspective view of a sterilizer for microphone;

FIG. 2 is a rear, bottom, left side perspective view of the sterilizer for microphone;

FIG. 3 is a front elevational view of the sterilizer for microphone;

FIG. 4 is a rear elevational view of the sterilizer for microphone;

FIG. 5 is a top plan view of the sterilizer for microphone;

FIG. 6 is a bottom plan view of the sterilizer for microphone;

FIG. 7 is a right side elevational view of the sterilizer for microphone;

FIG. 8 is a left side elevational view of the sterilizer for microphone;

FIG. 9 is an enlarged sectional view of the sterilizer for microphone taken along line 9-9 of FIG. 3;

FIG. 10 is a front, top, right side perspective view of the sterilizer for microphone showing a state in which the shade is opened;

FIG. 11 is a rear elevational view of the sterilizer for microphone showing a state in which the bracket is detached;

FIG. 12 is a reference view 1 of the sterilizer for microphone showing a state in which the connection position with the bracket is changed;

FIG. 13 is a reference view 2 of the sterilizer for microphone showing a state in which the connection position with the bracket is changed;

FIG. 14 is a reference view 3 of the sterilizer for microphone showing a state in which the connection position with the bracket is changed;

FIG. 15 is a reference view 1 of the sterilizer for microphone showing a state of use;

FIG. 16 is a reference view 2 of the sterilizer for microphone showing a state of use;

(Continued)

FIG. 17 is a reference view 3 of the sterilizer for microphone showing a state of use;

FIG. 18 is a reference right side elevational view of the sterilizer for microphone showing a state in which the shade and the bracket are detached; and,

FIG. 19 is a reference view of the sterilizer for microphone in a state of being installed on the wall.

The dot-dot-dash lines depicting the microphone stand and microphones in FIGS. 15-17 and the wall in FIG. 19 represent environmental subject matter and form no part of the claimed design; and the evenly broken lines illustrate portions of the sterilizer for microphone that form no part of the claimed design.
